UNITED STATES PATENT OFFICE.

WILLIAM M. BRUCE, JR., OF SPRINGFIELD, OHIO.

TELEGRAPHY.

1,317,859.

Specification of Letters Patent.

Patented Oct. 7, 1919.

Application filed March 4, 1915. Serial No. 12,083.

To all whom it may concern:

Be it known that I, WILLIAM M. BRUCE, Jr., a citizen of the United States, residing at Springfield, in the county of Clark and State of Ohio, have invented certain new and useful Improvements in Telegraphy, of which the following is a specification.

My invention relates to improvements in telegraphy and particularly relates to means for insuring an even distribution of current in cables or conductors of high capacity in sending signals so as to get a uniform marking of dots or dashes, both when the cable is normal or zero and also when the cable is not fully discharged and therefore not at zero.

I have heretofore employed a system of telegraphy in which current reversals are employed which are automatically regulated at the sending end so that current of different polarities are impressed upon the cable or conductor for the same length of time to insure the same rise in potential in the cable. When cables or high capacity conductors are being charged and discharged rapidly in sending a series of signals, particularly of different lengths such as dots and dashes, the cable does not always reach the normal or zero point between such signals as it does after a time interval between signals, hence the first impulse (or current reversal) of a series of impulses, owing to the condition of the cable, is apt to make a slightly longer character than the succeeding ones if they are short characters or in case there is a long character followed by a short character there may be a slight space between that and the succeeding character due to the same cause, namely that the cable or conductor may reach normal or zero in a long interval where it does not reach the same zero by a short interval.

To this end I provide means for controlling the amount of current impressed on the conductor at the sending end so as to cause the same rise in potential in the cable when the cable is not completely discharged as occurs when the cable is at zero.

In the accompanying drawings the figure is a diagram of circuits and apparatus embodying my invention.

In the said drawings I have shown apparatus for one end of the cable only, it being understood that this invention has to do only with the sending end and it is, of course understood that the cable will be properly

equipped with sending and receiving apparatus at each end thereof.

In the said drawings *k* is an ordinary telegraph key or transmitter which is in circuit with a relay *k*¹ and a battery *k*² to cause the relay *k*¹ to be operated whenever its circuit is opened or closed at the contact *k*³. The armature *a* of the relay *k*¹ is connected by wire 1 to a polarized sending relay *b* and thence to ground at *g*. This armature *a* is normally engaged with contact *a*¹ which is connected by wire 2 to contact *b*¹ of relay *b* and by wire 3 to the negative side of the main battery *B* and by branch wire 4 to a contact 5 of a cut-off relay *c*, the other contact 6 of said relay *c* being connected by branch wire 7 to wire 8 and to the positive side of the battery *B*, there being also a connection from this side of the battery through wires 8 and 9 to contact *a*² of the operating relay *k*¹ and also by wire 10 to contact *b*² of the sending relay *b*. The armature *b*³ of relay *b* is connected to the conductor or cable by a circuit over wire 12 which normally includes resistance *r*. This armature *b*³ is also connected by branch wire 13 to polarized relay *c*, the other side of said relay being connected through inductive resistance *r*¹ to ground at *g*¹. The sluggish relay *d* is arranged to receive the same impulses as the conductor and it may be connected directly into the circuit, which leads from the armature *b*³ of the sending relay *b* to the cable. I prefer, however, to connect it in parallel as shown by wire 11 and 11^a leading from the contacts *b*⁴ and *b*⁵ adapted to be engaged by the armature *b*³. By this construction the relay *d* gets a positive impulse when the armature *b*³ engages contacts *b*² and *b*⁵ from the main battery *B* through wire 11^a to ground at *g*²; when the armature *b*³ engages the contacts *b*¹ and *b*⁴ it gets a negative impulse from the battery *B* through the contacts *b*¹ and *b*⁴ and wire 11 to ground at *g*². This relay *d* would work if it got impulses from one side only of the armature *b*³ but it is preferable to have it take the impulses from both sides thereof so as to get exactly the same impulses that go into the conductor. When, however, it is connected as shown in the drawing so as to get first a positive and then a negative impulse these reversals of current would tend to neutralize the residual magnetism in the relay core and the relay might not retain its magnetism so readily.

were a single wound relay used. In order, therefore, that the armature core may be magnetized in the same direction at each impulse, I preferably provide this relay with 5 a differential winding as shown in the drawings so that the positive impulse moves around the core in one direction and the negative impulse moves around the core in the opposite direction so that the core is 10 magnetized in the same direction whether the impulse be positive or negative.

When the relay d is energized the resistance r is short circuited through wire 15 and contact d^2 in connection with the armature 15 d^1 and wire 14 and as the relay d will be magnetized as the first impulse is fed to the cable this first impulse will pass through the resistance r and any succeeding impulse will pass through the short circuit formed 20 by wires 14, contacts d^1 and d^2 and wire 15 provided the relay d remains energized. This relay d is so constructed that it will remain energized so long as the impulses follow each other in fairly rapid succession, 25 but if a time interval is allowed to lapse between impulses sufficient to bring the cable to zero, the relay d would be deenergized and the succeeding impulse would pass through the resistance or other obstruction 30 placed in the circuit at r . It will be understood that while I have shown ordinary resistance at r , any form of obstruction may be used at that point which will modify the current fed to the cable to the different conditions of the cable due to a complete discharge or only a partial discharge there. 35 While I have shown an operating relay k^1 in circuit with the key k and battery k^2 , it is obvious that the key might be substituted 40 for the armature a of the relay k^1 , so as to play between the two contacts a^1 and a^2 , in which case the battery k^2 and relay k^1 may be dispensed with.

The operation of the system is as follows:

45 On pressing the key k a positive impulse will be sent from battery B to the sending relay b from the positive pole of the battery B , through wires 8, 9, contact a^2 , armature a , wire 1, relay b and ground at g ; it 50 being understood that the armature a will be caused to engage contact a^2 by the energizing of the relay k^1 from the battery k^2 . This will cause the armature b^3 of the sending relay b to engage contact b^2 and positive 55 battery will be fed through wire 10, contact b^2 , armature b^3 , wire 12 and resistance r to the conductor or cable. The relay c will also get current through branch circuit 13 from wire 12 but owing to the inductive 60 resistance r^1 will operate at an interval of time later than the relay b . This will cause the armature c^1 of relay c to move from contact 5 to contact 6 and thus cut off the supply of positive current by grounding the positive 65 side of the battery at g^3 . The relay d being in a parallel circuit formed by the contacts b^2 and b^5 , wire 11^a to ground through one winding of the relay d , this relay will be energized, by the same impulse of positive current emanating from battery B and flowing in parallel to the cable and to the relay. 70 When relay d is energized the resistance r will be shunted out of the main conductor circuit and will be held shunted so long as the relay d remains energized. If, however, 75 the armature c^1 of the cut-off relay c should remain for sufficient period on the contact 6 so that the cable would be completely discharged, the relay d would have had time to be completely deenergized and open the 80 shunt at d^2 , thus leaving the obstruction r in the conductor feeding circuit. This could only happen in making a dash of sufficient length to let the cable get back to zero. Since the cut-off relay c works automatically 85 the cutting off the current and the deenergizing of the relay d will occur even though the key remain depressed and armature a^1 in contact with a^2 . If the current is broken at the key k so that the armature a moves to the back contact a^1 , the polarized sending relay b is energized by a current of opposite polarity and its armature b^3 engages contacts b^1 and b^4 and a negative impulse is impressed on the cable through wires 3 and 90 2, contact b^1 , armature b^3 , and wire 12 as before. The relay d will also get the same negative impulse through the parallel circuit from contact b^4 , wire 11, the other winding of the relay to ground at g^2 , thus again energizing the said relay. Now, if these positive and negative impulses follow each other with sufficient rapidity the relay d will remain energized and the obstruction r will be shunted from the circuit so long as a rapid 95 succession of impulses continues. Whenever the key remains at rest for a sufficient period in either position the relay d will be deenergized by the cutting off of its current 100 supply by the cut-off relay c and when this current supply is cut-off for a sufficient interval of time to permit the sluggish relay to release its armature, the obstruction r will remain in the sending circuit to the cable or conductor. The result of the arrangement 105 is that if positive and negative impulses follow each other with sufficient rapidity to cause the cable to retain a portion of the previous charge there will be fed to the cable a slightly larger charge of the opposite 110 polarity at the next impulse so as to compensate for the residual charge to be overcome and thus produce an equal rise of potential within the cable for each impulse as for the preceding one. The relay d being 115 so adjusted that the time interval during which it will hold up its armature after its circuit is broken is equal to the time interval necessary for the cable to be completely discharged, it will be seen that the rise in po 120 125 130

5 tential in the cable itself for each impulse will be the same whether it is an initial impulse (when the cable is completely discharged) or a succeeding impulse (when it is not completely discharged).

10 I have found that it is possible under certain conditions to do away with the resistance r entirely by having the relay d so adjusted that it will close its contacts at a slight interval after the impressing of an impulse upon the feed wire 12 in which case a portion only of the first impulse will be fed to the cable and this adjustment could be made so that a sufficient part of the first 15 impulse would pass to the cable from the feed wire 12 to produce the same potential rise in the cable, when at zero, as by the succeeding impulses when the cable is not at zero; that is, the relay d would operate at 20 a time interval after the operation of the relay b to cause only a portion of the current impressed on the wire 12 at the first impulse to pass into the cable by reason of the gap at the contact d^2 at the beginning 25 of the impulse which would be closed by the first impulse in time to secure the feeding of a proportional amount of said impulse to cause the same rise in potential as by the succeeding impulses. It will be understood 30 in this case that all of the impulses will pass through the feed wires 12, 14 and 15, but owing to the initial break in this feed circuit the first impulse made by the relay b would be fed to the cable through a 35 slightly less time interval than the succeeding impulses.

40 The arrangement with the resistance or some similar element r is considered preferable as it avoids the delicate adjustment of the relay to secure the result when this resistance is not used.

45 In the figure I have shown a modification in which a battery is used to keep a small charge on the cable at all times when it is not in use. This battery is so regulated that the charge thus assigned to the cable is equivalent to the residual charge which will be found in the cable after each impulse of a certain polarity and in order to make it 50 effective the charge which is at all times on the cable is of the opposite polarity from that of the last impulse impressed thereon. In connection therewith I provide a slow relay which is adapted at the first movement of the key to cut out this battery which is normally on the cable and cut in the battery which supplies the impulses so that the 55 first impulse impressed upon the cable finds the same conditions as the succeeding impulses and in this way the effect of impressing the impulses on a cable which is completely discharged is obviated and all the impulses will find exactly the same condition in the cable whether they are at the 60 end or the beginning of the series, or part 65

of a continuing series. In this connection it will be remembered that the reason for the distortion of a character at the beginning of a series of impulses is due to the fact that there is a certain amount of residual 70 charge in the cable when a series of impulses are following each other in rapid succession, and the means which are heretofore described for overcoming this is to give to the first impulse a slightly higher 75 resistance through which it passes or to cause it to be impressed upon the cable for a slightly shorter time in order that it may not cause a higher rise of potential in the cable (due to its wholly discharged condition) than when it follows along in a series 80 and meets residual charge in the cable.

85 In the figure of the drawings, the slow relay d^{12} is shown in multiple with the operating relay connected directly to the key, and therefore receives its impulse and operates to cut off the feeding battery B^2 before transmitting relay operates to transmit the impulse into the cable. The feeding battery B^2 is shown connected to a back contact d^3 90 of the slow relay d^{12} whose armature d^4 is connected directly to line 12 leading to the cable, variable resistance r^2 being interposed between the battery and the back contact d^3 by which the amount of battery fed 95 to the cable when idle can be regulated to correspond to the residual charge which would be in the cable after an impulse or a series of impulses. This adjustment can readily be ascertained by making impulses 100 both after a pause and in series until the result desired is obtained. The armature of the transmitting relay b is connected to the front contact d^5 on the slow relay d^{12} so that when the slow relay operates it connects the 105 transmitting relay direct to the cable and cuts off the feeding battery. Of course so long as the impulses from the keys follow each other in rapid succession the slow relay will be held up and the feeding battery will 110 be cut off.

Having thus described my invention, I claim:

1. In a telegraph circuit, an operating key and means operated thereby for impressing 115 current impulses of opposite polarity thereon, a relay controlled by said key, a feeding battery adapted to be connected to the circuit through a contact on said relay, and means for cutting off said feeding battery at 120 the first movement of said key, substantially as described.

2. In a system of telegraphy in which impulses of opposite polarity are impressed upon a conductor by means operated by a 125 single key, a feeding battery of one polarity normally connected to said conductor so as to charge said conductor with a polarity opposite to the last impulse transmitted thereto by said key, and a relay controlled by said 130

key so as to cut off said feed battery when an impulse of opposite polarity is to be transmitted thereto, substantially as described.

- 5 3. In a system of telegraphy, the combination with two polarized relays interdependent and coöperating so that one of said relays cuts off the current supply for the other and to a conductor whereby current impulses of
10 opposite polarity are impressed upon said conductor for a definite period, a feeding battery normally connected to the conductor so as to supply a charge thereto of opposite polarity from the last impulse impressed thereon by said polarized relays, and a cut-off relay operated by said key to cut off said feeding battery upon the first operation

of said key, said cut-off relay being so constructed as to remain energized so long as the key operations follow each other in rapid succession and thus retain the feeding battery out of circuit with said conductor and so long as said impulses are following each other with a pre-determined speed and to cut in said feeding battery upon a predetermined interval between a series of impulses as and for the purpose specified. 20 25

In testimony whereof I have hereunto set my hand this 6th day of February, 1915.
